UNITED STATES PATENT OFFICE.

WALDEMAR F. MAYER, OF PHILADELPHIA, PENNSYLVANIA, ASSIGNOR TO TAYLOR-WHARTON IRON AND STEEL COMPANY, OF HIGH BRIDGE, NEW JERSEY, A CORPORATION OF NEW JERSEY.

MEANS FOR OPERATING HYDRAULIC PULLBACK PRESSES.

Application filed November 12, 1919. Serial No. 337,426.

To all whom it may concern:

Be it known that I, WALDEMAR F. MAYER, a citizen of Switzerland, residing at Philadelphia, in the county of Philadelphia and 5 State of Pennsylvania, have invented certain new and useful Improvements in Means for Operating Hydraulic Pullback Presses, of which the following is a specification.

This invention relates to means for operating hydraulic pull-back presses and in providing a positive control, whereby to obtain any predetermined operating conditions through the governing operation of a single lever.

15 The invention is designed for application to hydraulic pull back presses, whether vertical or horizontal, wherein, through the single lever control, there can be obtained any desired pull-back speed, from zero to maximum; any desired stop position of the 20 press; a proper holding down of the ram on the work piece, without crushing pressure; and any work stroke, from zero to maximum.

25 In the drawings:—

Fig. 1 is a view in elevation, partly in section, illustrating the invention, and showing the control lever in position to insure a work stroke of the ram.

30 Fig. 2 is a detail view, showing the lever in the position to insure a hold down relation of the ram.

Fig. 3 is a similar view, showing the valve in the position to cause a pull back movement of the ram.

Fig. 4 is a similar view, showing the valve in the position to stop the ram.

Fig. 5 is a detail view illustrating the relief valve.

40 Fig. 6 is a sectional view of a well known type of variable delivery reversible flow pump.

The present invention is here shown as applied to a hydraulic press, comprising a 45 supporting frame 1, including columns supporting a cylinder 2, in which is arranged a ram 3, carrying a ram plate 4. The ends of the ram plate are provided with rods 5, having pistons 6, operating in pull-back 50 cylinders 7.

The power for the press is provided by a variable delivery and reversible flow pump 8, mounted beyond the press, and driven in any suitable manner, as by an electric motor

9. The pump 8 is of a type well known 55 in the art, and while shown conventionally in Fig. 6 of the drawings, needs no detailed description, forms no material part of the present invention, and is not claimed herein. The bed plate supporting the pump and 60 motor is formed to provide a reservoir 10, and arranged above the pump is a pressure tank 11, having conduits 12 and 13 extending therethrough. These conduits connect at the lower ends with the pump channels 12^a and 65 13^a, respectively, while at the upper ends the conduit 12 connects with the ram cylinder through a pipe 14, the conduit 13 connecting with the pull-back cylinders through a pipe 15.

The tank 11 is formed with a transverse valve passage 16, opening through the conduits 12 and 13, this passage being open to the interior of the tank at such conduits 12 and 13, so that under proper valve control, the ports 17 thus provided may be opened to the tank fluid and pressure. A 70 valve rod 18 is mounted for movement in the valve passage, and is provided with valves 19 and 20, arranged to govern the respective ports 17. The respective conduits 12 and 13 are enlarged in line with the valve positions therein, as at 21, so that the valves cannot entirely close the conduits under any conditions of operation, thereby providing by-passes around the valves.

The valves 19 and 20 are so arranged on the valve rod, as to prevent simultaneous closing of the ports 17 in any position of the valve rod, hence one or the other of the 80 conduits is always open to the tank 11.

The tank 11 is provided with a safety valve, as it is desired that a constant predetermined pressure be maintained in the tank. This valve is shown more particularly in 85 Fig. 5, and comprises a casing 22, having a discharge opening 23, and in which is slidably mounted a valve rod 24, carrying at its lower end an operating valve 25, normally closing the air-escape vent of the 90 tank. A ring 26, bearing partly upon the valve 25 and partly upon the adjacent surface of the tank, is subjected to a pressure spring 27, bearing between the top of the 95 casing and the ring. This spring is set for 100 a predetermined pressure, to thereby maintain a constant pressure limit in the tank. Above the casing 22, there is arranged 105

about the valve rod 24, an extension spring 28, between the top of the casing and a stop 29 on the valve rod. The spring 28 is weaker than the spring 27 and serves to support the 5 valve.

The desired pressure is introduced into the tank 11, through an auxiliary pump 30, driven preferably from the drive shaft of the pump 8, as by a chain and sprocket connection 31. Pump 30 is of ordinary rotary 10 single delivery type, and no detailed showing or description of such pump is deemed necessary herein. The auxiliary pump is open to the reservoir 10, and has a pipe connection 32 with the tank 11.

A manually operable lever 33 is connected with the valve rod 18, to simultaneously operate the valves 19 and 20. This control lever is operatively connected at the lower end 20 with the means 34 for changing the fluid delivery of the pump 8, and above such means with the pilot valve 35 thereof, the latter serving as a floating fulcrum for the lever. The delivery change means for the 25 pump 8 will therefore be governed in accordance with the movement of the lever, that is with the operation of valves 19 and 20.

The auxiliary pump 30 pumps the fluid 30 from the reservoir 10 into the tank 11, until the level of the fluid in the reservoir is below the intake of the pump, when the pump, in continued operation, delivers air under pressure to the tank. This operation places the 35 fluid in the tank 11 under a predetermined pressure, limited by the set of the safety valve 22.

With the control lever 33 in the position shown in Fig. 3 of the drawings, the improved means is arranged for the pull-back 40 operation. The motive fluid from the pump 8 may then be delivered through the conduit 13 to the pull-back cylinders 7, the valves 20 and 19 being in the relative positions to 45 close the conduit 13 against the tank 11, and to open the conduit 12 thereto. The fluid forced from the ram cylinder in the pull-back operation will then be discharged partly to the pump 8 and partly to the tank 50 11. By moving the control lever 33 toward the left, the pump delivery will gradually diminish, as the change control means of the pump, as 34, is moved toward the right. The pull-back speed will correspondingly 55 lower, until the parts reach the positions shown in Fig. 2, when the pump will be at zero delivery. With the pump delivery at zero, the ram will of course stop, this zero delivery position of the pump being provided for in the position of the control lever 60 33, as immediately above described. It will be noted that in the described position the valve is so arranged that the ram will be moved on the idle downward stroke on further 65 operation of the control lever 33 to

permit a fluid delivery from the pump. Notwithstanding this position of the valves, however, the ram will not be moved as long as the pump delivery is at zero. The pressure fluid from the tank that is the auxiliary 70 pump is applied to the ram and to the pull-back cylinder, but due to the larger area of the ram, the latter will move under this pressure until it finally seats on the work piece with that light pressure determined 75 by the set of the safety valve. The main pump will during this condition be at zero delivery position, or it can circulate the fluid at moderate speed, by passing around the valves as previously explained. In the operation 80 of the control lever farther toward the left, until the position in Fig. 1 is reached, the valve 19 will close the ram cylinder against the auxiliary pump pressure, and the press will operate at the full pressure of 85 the pump 8.

Having thus described the invention, what is claimed as new, is:—

1. In a means for operating hydraulic pull-back presses, a main pressure pump, an auxiliary pressure pump, and a single control lever to simultaneously set the main pump at zero delivery and open the ram and pull-back cylinders to the pressure of the auxiliary pump. 90

2. In a means for operating hydraulic pull-back presses, a main pressure pump, a constant-pressure tank, and a valve for simultaneously opening the pull-back cylinders to the main pressure pump and opening 100 the tank to the discharge from the ram cylinder. 95

3. In a means for operating hydraulic pull-back cylinders, a change speed variable delivery main pressure pump, conduits leading therefrom to the ram and pull-back cylinders, a constant pressure tank open to said conduits, and a single valve for controlling the delivery from the pump and the connections between the tank and conduits. 105

4. In a means for operating hydraulic pull-back presses, a variable-delivery main pressure pump, a constant pressure auxiliary pump, conduits leading from the main pump 115 to the ram and pull-back cylinders, valve-controlled communications between said conduits and the auxiliary pump, and a single lever to simultaneously control the main pump delivery and said valve-controlled 120 communications.

5. In a means for operating hydraulic pull-back presses, a variable delivery main pressure pump, a tank, means for maintaining a predetermined pressure in said tank, 125 conduits from the main pump leading through the tank and to the ram and pull-back cylinders, said conduits being formed with openings within the tank, valves for said openings, and a single lever to operate 130

said valves and simultaneously control the delivery of the main pump.

6. In a means for operating hydraulic pull-back presses, a variable delivery main pressure pump, a tank, an auxiliary pump for maintaining a pressure in said tank, a safety valve for limiting the pressure of the main tank, conduits from the main pump to

the ram and pull-back cylinders, valves for governing communication between said conduits and said tank, and means for operating said valves simultaneously with the control of the main pump delivery. 10

In testimony whereof I affix my signature.

WALDEMAR F. MAYER.
